ALEXANDER NYMAN, OF WILKINSBURG, PENNSYLVANIA, ASSIGNOR TO WESTINGHOUSE ELECTRIC & MANUFACTURING COMPANY, A CORPORATION OF PENNSYLVANIA.

WIRELESS TELEPHONE SYSTEM.

Application filed September 2, 1921. Serial No. 497,951.

My invention relates to wireless systems and more especially to wireless telephone modulating systems.

Broadly speaking, the object of my invention is to provide an improved system of modulation for use in connection with wireless telephone systems, whereby the transmission of speech by electromagnetic waves may be more readily effected.

More specifically, one object of my invention is to provide a modulating system which is applicable to wireless telephone systems radiating relatively large amounts of power.

Another object of my invention is to provide a modulating system of such characteristics that the microphone transmitter is required to handle only small amounts of energy.

Other objects of my invention will be apparent from the following description when taken in connection with the accompanying drawings and claims.

In the art of wireless telephony, various modulating systems have been proposed for modulating the high-frequency energy in accordance with the voice vibrations to be transmitted. In one such system, varying amounts of high-frequency energy are diverted from the antenna system and dissipated in an absorbing circuit in accordance with the varying intensity of sound waves. In another system, an energy-absorbing device is inserted directly in the antenna circuit and its impedance is varied in accordance with the signals to be transmitted.

In the wireless telephone system embodying my invention, however, modulation of the radiated energy is effected by varying the frequency and the amplitude of the high-frequency currents in an oscillatory circuit in accordance with sound waves, as hereinafter described. In a modification, the amplitude variations are still further increased by impressing the modulated radio-frequency currents upon a radiating circuit which is tuned to a frequency slightly different from that of the impressed currents.

My invention, however, may best be understood by reference to the accompanying drawings, wherein:

Fig. 1 is a diagrammatic view of a simple tuned circuit showing means for controlling the constants thereof in accordance with sound waves.

Fig. 2 is a diagrammatic view of circuits and apparatus embodying my invention in a wireless transmission system.

Fig. 3 is a similar view to that of Fig. 2, but showing an alternative system of modulation.

Fig. 4 is a view showing the diagrams referred to hereinafter.

In Fig. 1, I have shown a simple oscillating circuit 1 consisting of an inductance coil 2 and a condenser 3, the latter being shunted by a circuit 4 which includes a relatively small condenser 5 in series with a variable impedance element illustrated as a telephone transmitter 6. The resistance of the element 6 is such that slight variations therein cause large variations in the resultant capacity effect of the condensers 3 and 5. Thus, by varying the resistance of the element 6, it is possible to vary both the amplitude and the frequency of such currents as are caused to traverse the tuned circuit 1.

While I have shown a capacitive reactor 5 as connected in series with the variable-impedance element 6, the results just mentioned may also be obtained by replacing the capacitive reactor 5 by an inductive reactor. In the following diagrams, the variable impedance element 6 has been shown as a thermionic tube, though I do not wish to be limited to such device.

Referring to Fig. 2, I have shown a thermionic tube 7 adapted to serve as an oscillator tube in connection with a radiating system 8 of well known form. The radiating system comprises an antenna 9, a portion 11 of an inductance coil 12 and a ground lead 13.

The thermionic tube 7, which serves as an oscillation generator, comprises an anode 14, a grid 15 and a cathode 16, the latter being energized by means of a source of energy 17 through a resistor 18. A plate-filament circuit comprises a conductor 19 connecting the anode 14 to the tuning coil 12, a stopping condenser 20, which is included in said conductor, a portion 21 of the tuning coil 12, the ground conductor 13 and a conductor 22 connecting the ground conductor and the filament 16. The condenser 20 serves to prevent the tuning coil 12 from short-circuiting the direct-current source which energizes the tube, as will be hereinafter described. A grid-filament circuit comprises a conductor 23, which serves to connect the grid 15

to one end of the coupling coil 12, a portion 24 of the coupling coil 12, the ground conductor 13 and the conductor 22.

The oscillator tube 7 may be energized by 5 means of a direct-current generator 25, the positive terminal of which is connected to the anode 14 by a conductor 26, and the negative terminal of which is connected to the filament 16, by a conductor 27. A radio- 10 frequency choke coil 28 is serially included in the conductor 26. The thermionic tube 29 comprises an anode 30, a controlling grid 31 and a hot cathode 32; the latter being energized from a source of energy 33 15 through a resistor 34. The cathode 32 is directly connected to the negative terminal of the source of energy 25 and to the hot cathode 16 of the tube 7 by means of the conductor 27. The anode 30 is connected to 20 the conductor 26 through a resistor 35, the resistance thereof being determined by the plate-voltage rating of the tube 29.

A microphone transmitter 36 is operatively connected to a grid-filament circuit of 25 the modulator tube 29 through a coupling transformer 37, the primary winding 38 of which includes the microphone transmitter 36 and a source of energy 39, and the secondary winding 41 of which is included in 30 the grid-filament circuit just mentioned. A conductor, which includes an inductance coil 42 and a stopping condenser 42a, extends from the anode 30 of the modulator 29 to an adjustable point 43 on the tuning coil 12 35 and serves to connect the plate 30 and the filament 32 of the tube 29 in shunt to a portion 44 of the tuning coil 12.

In Fig. 3 is shown an oscillator generator 40 system 45 operatively associated with an antenna circuit 46. The antenna circuit 46 includes an antenna 47, a coupling coil 48, which is associated with the oscillation generator system 45 and a ground lead 49. An absorbing circuit 51, which comprises a 45 variable condenser 52, a coupling coil 53 and an energy-absorbing element 54, is also operatively associated with the oscillation-generator system 45.

Referring more specifically to the oscillation-generator system 45, I have shown an 50 oscillator tube 55 comprising an anode 56, a grid 57 and a hot cathode 58 which may be energized by means of a source of energy 59 through a resistor 61. The source of energy 25 may be connected to the tube by 55 conductors 62 and 63 which are connected to the anode 56 and to the hot cathode 58, respectively, through choke coils 64 and 65. A modulator tube 66, which is similar 60 to that shown in Fig. 2, may be energized from a separate source of energy 67 through a reactor 68.

The plate-filament circuit of the oscillation 65 generator 55 comprises a stopping condenser 69, a portion 70 of a coupling coil 71

and a return conductor 72. The grid-filament circuit includes a conductor 73, a portion 74 of the coil 71 and the return conductor 72. A circuit, which includes a fixed condenser 75 and a variable condenser 76, 70 is shown as shunted across the plate-filament circuit of the tube 55. A condenser 77 of relatively small capacity, in comparison with that of the condenser 75, is included in a conductor which extends from the anode 75 of the tube 66 to an intermediate point in the circuit connecting the condensers 75 and 76. The advantage of such capacity coupling of the modulator tube to the oscillation-generator system is that a much smaller 80 modulator tube may be employed by reason of the lower voltage and current requirements.

In operation, referring to Fig. 2 and assuming the thermionic tube 7 to be functioning as an oscillation generator, when voice vibrations enter the microphone 36, 85 varying potentials are impressed upon the grid 31 of the modulator tube 29, thereby causing corresponding variations in the impedance of the plate-filament circuit of the tube. Since the portion 44 of the coupling coil 12 is shunted by the inductance coil 42 and the condenser 42a in series, with the plate-filament circuit just mentioned, the 90 variations in the impedance produce corresponding changes in the amplitude and frequency of the radiated energy.

In the modification of my invention shown in Fig. 3, the radiating circuit 46 and the absorbing circuit 51 are tuned to different frequencies. The generator circuit 45 is tuned to frequencies intermediate the frequencies of the radiating and absorbing circuits, whereby a change in the frequency of 100 the generator circuit is accompanied by substantially equal and opposite changes in the currents drawn by the radiating and absorbing circuits, respectively. The total current, representing the load on the generator circuit, is, therefore, substantially constant. 105

Referring to Fig. 4, the currents I_{46} and I_{51} induced in the radiating and absorbing circuits, respectively, for different frequencies of the currents in the generator circuit 45, are indicated. The maximum currents drawn by the circuits 46 and 51 correspond to the frequencies F_{46} and F_{51} , respectively. 115

The generator circuit 45 is normally tuned to an intermediate frequency F_{45} at which point the slopes of the curves I_{46} and I_{51} are 120 constantly equal numerically but opposite in sign.

It is obvious, from the nature of the circuits shown in Fig. 3, that, by the proper adjustment of the reactors and of the constants of the modulator tube 66, the slope of the resistance curve of the modulator tube 66, plotted against the frequency of the genera- 125 130

tor circuit 45, may be caused to correspond approximately with the slope of the curve I_{46} , representing the current in the radiating circuit over a given operating range. 5 This has been indicated in Fig. 4 by means of a dotted-line curve R_{66} , representing the relation between the frequency of the generator circuit 45 and the resistance of the modulator tube 66. In this way, distortion 10 of the sound waves may be largely prevented.

While I have shown only three embodiments of my invention in the appended drawings, I do not wish to be limited thereby, but I desire that only such limitations 15 shall be imposed thereon as are indicated in the appended claims.

I claim as my invention:

1. In a wireless transmission system, an 20 oscillation-generator system including condensive and reactive elements, a constant supply of exciting energy therefor, an antenna circuit and an absorbing circuit operatively associated therewith, and a modulating circuit including reactance elements, one 25 of which is a variable-impedance element adapted to vary the amplitude and the frequency of the high-frequency energy generated by said oscillation-generator system in 30 accordance with sound waves, said antenna

and absorbing circuits being so tuned that said modulations in frequency effect opposite variations in the power absorbed by each circuit.

2. In a radio transmission system, the 35 combination with a radiating circuit, of a high-frequency supply circuit comprising inductive and capacitive reactors, a variable-impedance device connected in parallel relation to one of said reactors and comprising 40 in series a reactor of like sign and an approximately non-reactive impedance, means for varying the resistance of the non-reactive impedance and thereby varying the impedance of said variable-impedance device 45 in accordance with sound waves, whereby the frequency of said supply circuit may be varied within limits not including the frequency of said radiating circuit, said variable-impedance device being so adjusted that 50 the variations in the impedance thereof produce variations in frequency causing corresponding variations in the current in said radiating circuit, whereby sound distortion is largely prevented. 55

In testimony whereof, I have hereunto subscribed my name this 29th day of August, 1921.

ALEXANDER NYMAN.
